W. AVERY.
STEAM BOILER.

Patented June 28, 1836.

William Avery of Syracuse in the County of Onondaga State of New York. (485) Letters Patents

9785X

The schedule referred to in these Letters Patent and making part of the same, containing a description in the words of the said William Avery himself of his improvement in the boiler for generating steam for all whom it may concern. Be it known that I

William Avery of Syracuse, in the County of Onondaga in the State of New York have invented an improved boiler for generating steam for steam engines, and for other purposes, and I do hereby declare that the following is a full and exact description thereof reference being had to the drawings which accompany and make a part of the description.

In describing this boiler I shall use a guide in its construction, mention and dimensions of the respective parts, as according to my observations are most proper to each other, but with an understanding thereby to limit myself in this particular, as it is evident that the absolute size must be governed by the purpose to which it is to be applied and that this proportion of the individual parts to each other will admit of considerable variation, whilst the principle of constructing remains unchanged.

The exterior appearance of the boiler is that of a vertical cylinder, Fig. 1 being the lower portion of the cylinder upon which the part A, Fig. 2 is to be placed, the two being united together by bolts and flanges with a gasket interposed. The furnace is contained within, Fig. 3 being a second or interior cylinder with a space D, between them, which space is filled with water. The aperture for the feeding door and also that for an ash pit door, are of course so lined through the water space as to connect the outer and inner cylinders. The inner cylinder forming the crust or walls of the furnace is surrounded by a part C, B, which is made of square iron immediately above that cylinder and forms part of the fire, and of the boiler C, B, are the openings of tubes which extend from side

to side of this square the alternate rows of tubes being at right angles to each other as seen at C fig 3.

The part marked B is a continuation of the flue, connecting the square part B with the round chimney and is therefore square at its lower and round at its upper end -

The cylinders A may be three feet in diameter and eight feet in height, the flange for fastening them together two feet from the bottom. The space D between the two cylinders may be four inches. B B is twenty inches square and three feet high; it is pierced so as to receive in each plate, the ends of twenty four iron tube, making in the whole 144 tubes, the holes are at equal distances from each other and the tubes must be firmly fixed by riveting or otherwise -

The conical part E terminates at its upper end by a circle of twelve inches diameter E E fig 1 & 2 are flanges by which the upper end of the boiler and the flue are attached together by bolts, a gasket, &c. steam and water-cock, a safety valve and the usual appendages to a steam boiler, are of course employed, but these do not need my description. A boiler, the general construction of which is that above described, offers several advantages over most if not all others. The square portion immediately above the furnace, and which receives the tubes in the way described, will admit of expansion and contraction in such a way as will not tend to loosen the tubes even should the expansion or contraction be from any cause rendered unequal. The water space by the peculiar construction of the boiler is greatest at the mouth of the tubes where it is most needed, and where the heat is most intense, namely on the lower tubes, there will at all times be a pressure of at least three feet head of water. Should the water accidentally be allowed to descend below the upper range of tubes, the portion of heat from the furnace which will reach them will not be likely to be productive of drying -

What I claim therefore as my contribution my invention, improvement, is the general construction form and combination

of the respective parts as above described, by which general combination I do not merely intend a novel boiler with a double case between which the water to be heated is contained, the furnace being situated within the inner case and having tubes for heating water, such boilers having been heretofore constructed; but a distinguishing characteristic of my boiler is the combination of these parts with the square portion, which receives the tubes, and which is marked B in the drawings together with such variations of which the same is susceptible, whilst the general characteristics by which it is desired to remain substantially the same.
